[57] CLAIM

The ornamental design for a plastic pallet assembly, as shown and described.

DESCRIPTION

FIG. 1 is a perspective top view of a plastic pallet assembly comprised of a base, a deck and a plurality of connectors showing our new design;

FIG. 2 is a top plan view of the deck thereof;

FIG. 3 is a bottom plan view of the base thereof;

FIG. 4 is a right elevation view of the pallet with the left elevation view being a mirror image thereof;

FIG. 5 is a front elevation view of the pallet with the rear elevation view being a mirror image thereof;

FIG. 6 is a top plan view of the base thereof; and,

FIG. 7 is a bottom plan view of the deck thereof.
